(57) **CLAIM**

The ornamental design for an unmanned aerial vehicle, as shown and described.

DESCRIPTION

FIG. 1 is a front perspective view of an unmanned aerial vehicle, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a bottom view thereof;

FIG. 8 is a top view thereof;

FIG. 9 is a partial enlargement of FIG. 1;

FIG. 10 is a partial enlargement of FIG. 1; and,

FIG. 11 is a partial enlargement of FIG. 2.

The broken lines in the drawings illustrate the portions of the unmanned aerial vehicle, which form no part of the claimed design. The additional dot-dash lines surrounding the detail views are for annotative purposes only and form no part thereof.
